UNITED STATES PATENT OFFICE.

WILLIAM E. SOMERVILLE, OF COAL CITY, ILLINOIS.

AUTOMATIC SWIFT.

1,122,312.

Specification of Letters Patent. Patented Dec. 29, 1914.

Application filed August 27, 1910. Serial No. 579,303.

To all whom it may concern:

Be it known that I, WILLIAM E. SOMERVILLE, a citizen of the United States, residing at Coal City, in the county of Grundy and State of Illinois, have invented new and useful Improvements in Automatic Swifts, of which the following is a full, clear, concise, and exact description, reference being had to the accompanying drawing, forming a part of this specification.

My invention relates to improvements in automatic swifts or devices by means of which rolls or coils of wire are unwound, and has for its object the production of a device by the use of which the tangling, snarling, or breaking of the wire while in the process of being unwound is prevented.

A further object is the production of a device that can be adjusted to fit any size of coil of wire.

A further object is the production of a device that will automatically adjust itself to the constantly increasing internal diameter of the coil as the wire is unwound.

25 A further object is the production of a device that can be cheaply manufactured, and consists of comparatively few parts, and is not liable to be broken or get out of order.

30 These, and other objects such as may hereinafter appear, are obtained by my device, an embodiment of which is illustrated in the accompanying drawings, in which—

Figure 1 represents a side elevation of my device in operative position; Fig. 2 represents a top plan view of my device in operative position; Fig. 3 represents an enlarged sectional view, showing only the swift and base; Fig. 4 represents an enlarged sectional view similar to Fig. 3, with the arms extended; Fig. 5 is a detail view of the locking collar; Fig. 6 is a sectional view on the line 6—6 of Fig. 3 looking in the direction of the arrows; and Fig. 7 is 45 a top plan view of my device with the wire and base removed.

Like numerals of reference indicate like parts in the several figures of the drawings.

50 Referring now to the drawings, in Fig. 1 I have shown a supporting frame A, on which is mounted a swift B, carrying a coil or roll of wire C. The speed of the swift may be regulated by means of a suitable brake D. The frame A comprises a base 8, an upright 9 bored to receive an

upright stationary shaft 10. An arm 11 projects from the upright on which is the supporting arm 12 carrying the tension wheel 13. A tubular shaft or sleeve 14 surrounds the shaft 10, on the base of which above the upright 9 is keyed a brake wheel 15. Any suitable braking means may be employed, for instance, a brake 16 operated through a foot lever 17 hung on the support 12 and secured at 18 to the upright 19, the upper end of which is connected to the brake support 20 by means of hooks 21.

Referring now to the swift proper, a circular base or support 22, provided with a plurality of radially extending openings or slots 23, is bolted to the base collar 24 keyed on the sleeve. An upper collar 25 is also keyed on the sleeve, and the central collar 26 is loosely mounted on the sleeve between the collars 24 and 25. An ordinary split collar 27, provided with inwardly projecting lugs or pins 28, is mounted on the sleeve above the central collar. The sleeve is provided with oppositely disposed openings or sockets 29 within which the lugs or pins of the collar fit, and by means of which the distance of the upward movement of the central collar may be regulated. A plurality of upright supporting bars or arms 30, in this form, six in number, are arranged concentrically about the central shaft, the lower ends passing through the openings 23 in the base 22 and connected to the collars on the central sleeve by means of links 31. The links are pivotally mounted at their inner ends to the collars 24, 25 and 26 and at their outer ends pivotally mounted on the castings 32 secured to the inner faces of the bars or arms 30, the axes 33 of the links being horizontal so that the links shall be free to swing in vertical radial planes. Pivotally mounted on the lower end of one of the bars 30 is a dog 33 and on the base 22 a corresponding rack or series of openings 34 is provided in position to engage the end of the dog and to limit the outward movement of the arms 30 when the machine is not in operation.

In the operation of my device, the positions of the arms 30 are adjusted to the proper size by adjusting the collar 27 at the proper position on the sleeve and the middle yoke or collar slid up or down as required to accommodate the size of the coil to be unwound, it being simply necessary in placing the coil in position about the

shaft to permit the lugs or pins to enter the proper sockets and clamp the collar in place. The dog 33 is then thrown out of engagement and the inner end of the wire is carried over the tension wheel 13 and connected with a spool or bobbin on which it is to be rewound, and as the wire is wound on the bobbin, the swift revolves, the speed of the swift of course being regulated by the speed of the bobbin. As the swift revolves and the inner layers of wire are uncoiled, centrifugal action forces the arms 30 outwardly against the inner face of the coil and keeps the mat all times in such position. In the event that, by reason of low speed the centrifugal force is not sufficient at times, the wire will slip downwardly slightly on the swift and the arms kept in engagement or pressing against the inner face of the coil.

In the ordinary tapering swifts without movable arms the wire will gradually slip down on the swift as far as it can get, and then unless the speed at which the bobbins, on which the wire is being wound, is reduced, the wire in the coil will be apt to tangle and break. It has always been necessary heretofore to gradually reduce the speed as the coil is nearly unwound, but in my improved device the uniform high rate of speed can be maintained at all times owing to the fact that the centrifugal action keeps the arms always in close contact with the inner face of the coil.

35 My improved swift is instantly adjustable to accommodate all sizes of coils of wire and can be run at a much higher rate of speed than is possible with any swift on the market, and in addition thereto, it is possible to place the wire under any desired degree of tension without danger of breaking or tangling the wire. By the use of my improved swift constant pressure is maintained on the inside of the coil with a gradual increase in diameter as the internal diameter of the coil increases. It will be seen also that the feature of having the lower ends of the coil supporting uprights 30 work in radial slots 23 in the base plates 50 22 is important in that this construction insures the maintenance of the spaced relation of the aforesaid bars 30; in other words, the slots in the base plate afford radial guides for the bars and thus prevent the strains of supporting the coil and unwinding the same forcing these bars out of position. It will also be understood that my apparatus is intended especially for use in connection with wire of high carbon steel, which wire is very easily tangled. In operation the swift revolves at a very high speed which keeps the hank or coil on the swift in constant vibration, and between this vibration and the centrifugal action of the upright bars, the hank or coil is so held

that the inner coils that are being unwound have no opportunity to get tangled during the unwinding. It is important that the wire shall be unwound under tension, which tension can be applied by the attendant by means of the manually operable brake; and it is desirable also that the direction of pull on the wire shall be downwardly over the hank or coil, as shown in dotted lines in Fig. 1, the wire in this instance passing under the guide roller 13 instead of above it as shown in full lines. In view of the high speed, if the wire were unwound from the outside of the coil, the unwinding action would have to be performed very slowly in order to prevent tangling, especially if it be unwound without the proper tension being maintained on the wire.

While I have illustrated a means through the medium of which the desired result may be obtained, it is to be understood that I do not limit myself to such specific construction, as other forms are possible without departing from the spirit of my invention, which is, broadly speaking, the automatic regulation of the circumference of the swift to meet any required conditions under which the swift is used.

I claim:

1. A swift comprising a central vertical rotatable shaft, a series of upwardly-converging coil-supporting bars spaced around said shaft, a series of links connecting each of said bars to said shaft, these links having a free vertical swinging action, whereby said coil supporting bars shall be free to move bodily outward by the centrifugal action to compensate for the gradual increase in the inner diameter of the coil, means for variably retarding the rotation of said shaft and means for radially guiding and laterally supporting the lower ends of said coil supporting bars in their radial movement.

2. A swift comprising a vertical stationary shaft, a sleeve-shaft rotatively supported thereon, a series of upwardly converging coil supporting bars spaced around said sleeve-shaft, a plurality of vertically swinging links connecting each of said bars with said sleeve shaft, whereby the rotation of the sleeve shaft will cause the coil supporting bars to bodily move radially outwardly by centrifugal action to compensate for the gradual increase in the inner diameter of the coil of wire supported on the bars, and means for variably retarding the rotation of said sleeve shaft to maintain the proper tension of the wire as it comes from the coil.

3. A swift comprising a vertical stationary shaft, a sleeve-shaft rotatively sup-

23 said thereon, a series of upwardly-converging
24 coil-supporting bars spaced around said
25 sleeve-shaft, a plurality of vertically swing-
26 ing links connecting each of said bars with
27 said sleeve-shaft, whereby the rotation of
28 the sleeve shaft will cause the coil support-
29 ing bars to bodily move radially outwardly
30 by centrifugal action to compensate for the
31 gradual increase in the inner diameter of
32 the coil of wire supported on the bars, an
33 adjustable stop-collar on said sleeve shaft,
34 a sliding collar below said stop collar, a
35 series of links connecting said sliding collar
36 to the coil-supporting bars, and means for
37 manually retarding the rotation of said
38 sleeve shaft to maintain the proper tension
39 of the wire as it comes from the coil.

4. A swift comprising a central vertical
5 rotatable shaft, a series of upwardly-con-
6 verging coil-supporting bars spaced around
7 said shaft, a series of links connecting each
8 of said bars to said shaft, these links having
9 a free vertical swinging action, whereby said

coil supporting bars shall be free to move
bodily outwardly by the centrifugal action 25
to compensate for the gradual increase in
the inner diameter of the coil, means for
radially guiding and laterally supporting
said coil supporting bars at their lower
ends in their radial movement, a manually 30
operable holding device coöperating between
the coil-supporting bars and the guiding
means for holding the coil-supporting bars
in their adjusted position while the coil is
being placed thereon, and means for man- 35
ually retarding the rotation of the shaft to
maintain the proper tension of the wire as
it comes from the coil.

In testimony whereof, I have hereunto
subscribed my name in the presence of two 40
witnesses.

WILLIAM E. SOMERVILLE.
